US00D923018S

(12) **United States Design Patent** (10) **Patent No.:** **US D923,018 S**
Lu (45) **Date of Patent:** **** Jun. 22, 2021**

(54) **DISPLAY MOUNT**

(71) Applicant: **SHENZHEN PRIME TECHNOLOGY CO., LTD**, Shenzhen (CN)

(72) Inventor: **Chengan Lu**, Shenzhen (CN)

(73) Assignee: **SHENZHEN PRIME TECHNOLOGY CO., LTD**, Shenzhen (CN)

(**) Term: **15 Years**

(21) Appl. No.: **29/750,878**

(22) Filed: **Sep. 17, 2020**

(51) **LOC (13) Cl.** **14-02**

(52) **U.S. Cl.**

USPC **D14/452**; D14/239

(57) **CLAIM**

The ornamental design for a display mount, as shown and described.

DESCRIPTION

FIG. 1 is a perspective view of a display mount showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the display mount that form no part of the claimed design.

1 Claim, 8 Drawing Sheets
